UNITED STATES PATENT OFFICE.

AUGUSTUS F. HARTER, OF CHICAGO, ILLINOIS, ASSIGNOR TO CRIBBEN & SEXTON COMPANY, OF CHICAGO, ILLINOIS, A CORPORATION OF ILLINOIS.

DESIGN FOR A COOKING-RANGE.

SPECIFICATION forming part of Design No. 36,310, dated May 5, 1903.

Application filed April 10, 1903. Serial No. 152,085. Term of patent 7 years.

To all whom it may concern:

Be it known that I, AUGUSTUS F. HARTER, a citizen of the United States, residing at Chicago, in the county of Cook and State of Illinois, have invented a new, original, and ornamental Design for a Cooking-Range, of which the following is a specification, reference being had to the accompanying drawing, forming part thereof.

10 The figure is a perspective view of a cooking-range, showing my new design.

As shown in the drawing, my design consists of ornamentations arranged around the base of the range. The exterior surfaces of 15 the doors through which fuel is inserted and through which ashes are removed are ornamented by ribs and depressions arranged so as to produce the appearance shown in the drawing. The exterior surface of the oven-door, as well as the surface of the laterally-

projecting portion of the side of the range, is also ornamented by raised and depressed portions, as shown. On the front surface of the flue, above the cooking-surface, is located an ornamental plate. The top of the range 25 is ornamented by outwardly-facing castings resembling the head of an animal.

Having described my invention, what I claim as new, and desire to secure by Letters Patent, is—

30 The ornamental design for a cooking-range, as herein shown and described.

In witness whereof I have hereunto subscribed my name in the presence of two subscribing witnesses.

AUGUSTUS F. HARTER.

In presence of—

PETER BAUM,
W. A. SMITH.
